UNITED STATES PATENT OFFICE.

CHESTER SHANK, OF MARION, MICHIGAN.

DESIGN FOR A SEWING-STAND.

44,076.

Specification for Design.

Patented May 20, 1913.

Application filed March 5, 1913. Serial No. 752,227. Term of patent 14 years.

To all whom it may concern:

Be it known that I, CHESTER SHANK, a citizen of the United States, residing at Marion, in the county of Osceola and State of Michigan, have invented a new, original, and ornamental Design for a Sewing-Stand, of which the following is a specification, reference being had to the accompanying drawing, forming part thereof.

The figure is a perspective view of a sewing stand showing my design.

I claim:

The ornamental design for a sewing stand, as shown.

CHESTER SHANK.

Witnesses:

CHAS. F. GRIM,
R. E. ROUSE.
